Raymond Romine
INVENTOR
BY *Victor J. Evans*
ATTORNEY

UNITED STATES PATENT OFFICE.

RAYMOND ROMINE, OF WALDO, WEST VIRGINIA.

NOVELTY.

Application filed June 16, 1922. Serial No. 568,744.

To whom it may concern:

Be it known that I, RAYMOND ROMINE, a citizen of the United States, residing at Waldo, in the county of Putnam and State 5 of West Virginia, have invented new and useful Improvements in Novelties, of which the following is a specification.

My present invention has reference to an advertising novelty.

10 In carrying out my invention, I propose to produce an inflatable frame which is preferably a replica of an ordinary pneumatic casing and which is also preferably designed to be supported on the spare tire carrier of 15 an automobile, said frame supporting plates, the inner plate containing advertising matter and the outer plate being transparent.

Other objects will present themselves as 20 the nature of the invention is better understood, reference being had to the drawing which accompanies and which forms part of this application.

In the drawing:—

Figure 1 is a view of an advertising novelty in accordance with this invention, illustrating the same in applied position on the 25 spare tire carrier of an automobile.

Figure 2 is a sectional view on a greatly 30 enlarged scale and approximately on the line 2—2 of Figure 1.

As disclosed by the drawing, I make use 35 of an elastic tube 1 in the nature of an annulus. The tube 1 is inflatable and is provided with a normally closed air inlet valve 2 of the usual construction. The tube is shaped to represent a tire casing, the inner edge of which being flat and being provided

with a continuous groove 3. If desired, there may be arranged in the groove a continuous compressible ring 4. The groove is also designed to receive therein a plurality of flat disks, the inner disk 5 being preferably in the nature of a backing for the intermediate disk 6. The intermediate disk has on its outer face suitable advertising matter, and 45 the outermost disk 7 is transparent and provides a facing for the advertising disk 6.

By deflating the tube 1 the disks may be readily arranged in the groove, and by inflating the said tube, the disks are effectively 50 sustained in the groove.

Having described the invention, I claim:—

1. In an advertising novelty, an elastic continuous tube having an air inlet valve whereby the same may be inflated, said tube comprising a frame, disks having their edges seated in the inner edge of the frame sustained therein upon the inflation of the frame, one of said disks containing advertising matter, another disk providing a facing therefor, and the remaining disk providing a backing for the first mentioned disk. 60

2. In an advertising novelty, a continuous elastic tube having an air valve whereby the same may be inflated, said tube having an 65 inner peripheral groove, a compressible ring therein, a disk containing advertising matter received in the groove and having its edge contacted by the compressible ring, and said disk being sustained in the groove upon 70 the inflation of the tube.

In testimony whereof I affix my signature.

RAYMOND ROMINE.
